JOHN FORTIER, OF FAIRPORT, NEW YORK.

Letters Patent No. 73,964, dated February 4, 1868.

IMPROVED CAR-COUPLING.

The Schedule referred to in these Letters Patent and making part of the same.

TO ALL WHOM IT MAY CONCERN:

Be it known that I, JOHN FORTIER, of Fairport, in the county of Monroe, and State of New York, have invented a certain new and useful Improvement in Car-Couplings; and I do hereby declare that the following is a full and exact description thereof, reference being had to the accompanying drawings, making part of this specification:

Figure 1 is a sectional elevation of the contiguous draw-heads of two cars coupled in my improved manner.

Figure 2, a perspective view of the removable head detached.

Figure 3, a perspective view of the slide and the rubber spring detached.

Like letters of reference indicate corresponding parts in all the figures.

My invention consists in the special arrangement of a slide and rubber spring, the slide enclosing or covering the spring to shield it, and the spring acting by tension to produce the necessary reaction, and having its ends so arranged as to receive the shock at the extent of back motion, and thereby prevent injury. The said slide and spring are intended to be used in connection with the ordinary coupling-pin and link, in such a manner as to hold the pin up until the link couples, when said pin falls, and the link is held extended in the condition for coupling in the opposite direction.

As represented in the drawings, A A are the contiguous draw-heads of two cars, coupled together by the ordinary link and pin, B C. The draw-heads themselves are the same as those ordinarily used, except that they are provided with removable heads, *aa*, in order to adapt my special invention to the ordinary couplings. Each head is cast in a single piece, and provided with a flaring mouth, *b*, which centres the link as it strikes a narrow throat, *c*, which holds the link extended, and a socket, *d*, for receiving the coupling-pin. The head is simply slipped over the draw-bar till the shoulders strike, and it is then secured by screws or otherwise. By this means I am enabled to adapt my invention to ordinary couplings, the flaring mouth of the draw-heads being necessary to centre the link.

Between the sides *ff* of the draw-bar is situated a slide, *D*, consisting of a body, *g*, and ends *h h*, bent downward, as shown. A rubber spring, *E*, attaches to the rear end of the slide, and passes forward under its body, and attaches at *i* to a stationary part of the draw-bar. The ends *k k* of the spring are made to project, as shown, so that, at the extent of the back motion, the shock will come against them, and thus relieve the blow.

The action will be readily understood. When the coupling-pin is raised the slide will be drawn forward, so that the pin will rest upon it, as shown in red lines, fig. 1. In the act of coupling, the link, striking the end of the slide, will throw the latter from under the pin, which will then fall and catch the link. When thus caught the pressure of the slide forward against the link and pin will cause the link to be held extended in the proper position for coupling with the next car. By this means there is no need of an operator going between the cars, but the coupling will be self-acting.

The great advantage of this invention results from the special arrangement of the slide and rubber spring, the slide enclosing or covering the spring so as to keep it in place and shield it at all times, and the spring acting by tension to produce the necessary reaction. Couplings are already known in which a slide is pressed forward by a coiled metallic spring in the rear, to hold the coupling-pin elevated. Metallic springs are liable to break in cold weather, or, if frozen in, especially when compressed. In my case the rubber spring is enclosed in the slide, so that no water or snow can reach it, and it therefore cannot freeze in. The construction is also such as to keep the spring in its place and equalize its action. Besides this, the spring, acting by tension, is much more elastic and effective than it would be if acting by compression, and drawing forward lengthwise of the slide itself it acts more readily upon it.

I do not claim a slide pressed forward by a metallic spring, as I am aware that the same is not new; but what I claim as my invention, is—

The combination of the spring *E* with the enclosing slide *D* and case *f*, arranged in such a manner that the spring acts by the tension of its main body and compression of its parts *k k* simultaneously to resist the thrust of the coupling-link, substantially as set forth.

In witness whereof, I have hereunto signed my name in the presence of two subscribing witnesses:

JOHN FORTIER.
